UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

RECTIFYING ARRANGEMENT FOR ALTERNATING CURRENTS.

Application filed July 15, 1920, Serial No. 396,500, and in France August 14, 1917.

(GRANTED UNDER THE PROVISIONS OF THE ACT OF MARCH 3, 1921, 41 STAT. L., 1313.)

My invention relates to rectifying systems and more particularly to rectifying systems employing thermionic valves.

One of the principal objects of my invention is the provision of a rectifying system possessing the following advantages:

1. Heating of the filamentary cathodes of the valves in said system by alternating current and,
- 10 2. Protection of the valves in said system against excessive current.

Other objects and advantages of my invention will be apparent from the following description taken in connection with the accompanying drawings in which:

Fig. 1 is a schematic diagram of a preferred embodiment of my rectifying system and

Fig. 2 is a schematic diagram of a modification of my invention.

Referring to Fig. 1, 1 and 2 are two-element thermionic valves each comprising an anode 3 and a filamentary cathode 4. The anode of valve 1 is connected to the filamentary cathode of valve 2 and the anode of valve 2 is connected to the filamentary cathode of valve 1 through two condensers 5 and 6 connected in series as shown.

The primary winding 20 of transformer 30 7 is connected across a source of alternating current power 8. One extremity of the secondary winding 21 of transformer 7 is connected to the anode of valve 1 and the filamentary cathode of valve 2 as shown; while the other extremity of the secondary winding 21 is connected between the two condensers 5 and 6.

The filamentary cathodes 4 of the two valves are energized by means of transformer 9 having two outside legs and one middle leg as shown. The primary winding 22 of transformer 9 is mounted on the middle leg and connected across the source of alternating current power 8. The secondary 45 windings 23 and 24 are mounted on the two outside legs, those windings being so arranged that their ampere turns normally balance resulting in substantially zero magnetic interaction between them. The filamentary cathode of valve 1 is connected across secondary winding 23 and the fila-

mentary cathode of valve 2 is connected across the other secondary winding 24. Rectified current is supplied by the leads 10 and 11 as shown.

Referring to Fig. 2, each filamentary cathode 4 is connected across a source of alternating current power 8 through a coil 12. These coils are mounted on a magnetic core 13 and are so arranged on the core that their ampere turns normally balance resulting in substantially zero magnetic interaction between them.

The system disclosed in Fig. 1 functions in the following manner: The valve 1 rectifies one half of the alternating current wave while the valve 2 rectifies the other half of the wave, the condensers 5 and 6 serving to iron out the rectified current pulsations and also preventing short-circuits between the anodes and filamentary cathodes of the various valves.

The filamentary cathodes 4 are energized by means of the secondary windings 23 and 24 of transformer 9, the ampere turns of these windings normally balancing each other. If one of the valves should burn out, the load on the other valve will increase very materially unless its filamentary cathode current is very materially decreased. This is accomplished by transformer 9 in the following manner: As soon as the filamentary cathode of one of the valves burns out the secondary winding to which it is connected is substantially open-circuited. This destroys the magnetic balance between the two secondary windings resulting in a very substantial increase in the impedance of the secondary winding connected to the undamaged filamentary cathode. This results in the substantial diminution of the current in the undamaged filamentary cathode thereby cutting down the load on the undamaged valve and preventing its burning out.

The modified system disclosed in Fig. 2 functions as follows: The coils 12 normally balance each other magnetically. Their individual impedances are therefore very small. If one of the filamentary cathodes burns out, one of the coils is substantially open-circuited resulting in a substantial in-

crease in the impedance of the other coil. This increase in impedance substantially diminishes the current flowing in the undamaged filamentary cathode and prevents its 5 burning out.

While I have shown and described various preferred embodiments of my invention, I do not limit myself to the same; but may employ such other modifications as come 10 within the spirit and scope of my invention.

Claims:

1. In a system for rectifying alternating current, a source of alternating current of a certain voltage, a plurality of electron discharge devices each provided with a cathode and an anode, a physically separate wholly metallic circuit in series with each cathode, a separate transformer winding in series with each circuit, each transformer winding being inductively connected to said source for supplying alternating heating current to its circuit derived from said source, means for applying alternately to said anodes positive potentials developed from said 25 source whereby space currents flow alternately between the cathodes and the anodes of the respective devices, a plurality of capacities and connections for causing said space currents to charge said capacities one 30 at a time and for causing said capacities to discharge in series, whereby unidirectional current of a higher voltage than said source is developed.
2. In a current rectifying arrangement, 35 of pair of electron discharge rectifiers, each provided with a filament and an anode, two physically separate transformer windings, one of said windings being connected in series with one of said filaments and the 40 other of said windings being connected in series with the other of said filaments, and an additional transformer winding, the anode of a first one of said rectifiers and the filament of a second one of said rectifiers 45 being connected to one terminal of said additional winding, the filament of said first rectifier being connected to the other terminal of said additional winding through a capacity and the anode of said other recti-

fier being connected to said last-mentioned 50 terminal of said third winding through a second capacity.

3. In a current rectifying arrangement, a source of alternating current to be rectified, a pair of electron discharge rectifiers, each 55 provided with a filament and an anode, two physically separate transformer windings, one of said windings being connected in series with one of said filaments and the other of said windings being connected in 60 series with the other of said filaments, an additional transformer winding, and means for connecting said transformer windings inductively to said source of alternating current, the anode of a first one of said rectifiers and the filament of a second one of said rectifiers being connected to one terminal of 65 said additional winding, the filament of said first rectifier being connected to the other terminal of said additional winding through a capacity and the anode of said other rectifier being connected to said last-mentioned 70 terminal of said additional winding through a second capacity.

4. In a current rectifying arrangement, a 75 pair of electron discharge rectifiers each provided with a filament and an anode, two physically separate transformer windings 80 normally magnetically balanced with respect to each other, one of said windings being connected in series with one of said filaments, and the other winding being connected in series with the other of said filaments, and an additional transformer winding, the anode of a first one of said rectifiers 85 and the filament of a second one of said rectifiers being connected to one terminal of said additional winding, the filament of said first mentioned rectifier being connected to the other terminal of said additional winding through a capacity, and the anode of said other rectifier being connected to said last-mentioned terminal of said additional winding through a second capacity.

In witness whereof, I have hereunto signed 90 my name.

MARIUS LATOUR.
